Primary Examiner — Austin Murphy*(74) Attorney, Agent, or Firm* — Carina Tan; Corsair Memory, Inc.(57) **CLAIM**

The ornamental design for a mouse with wing, as shown and described.

DESCRIPTION

FIG. 1 is a right perspective view of a mouse with wing showing our design;

FIG. 2 is a left perspective view of the mouse with wing;

FIG. 3 is a left view of the mouse with wing;

FIG. 4 is a right view of the mouse with wing;

FIG. 5 is a front view of the mouse with wing;

FIG. 6 is a rear view of the mouse with wing;

FIG. 7 is a top view of the mouse with wing; and,

FIG. 8 is a bottom view of the mouse with wing.

The shade lines in the figures show contour and the cross-hatch lines show surface texture.
